WHEEL CHOCK

Daniel Hudak, Peekskill, and John Kostenko, Hopewell Junction, N.Y., assignors to General Casting Corporation, Jefferson Valley, N.Y., a corporation of New York

Filed July 25, 1969, Ser. No. 18,398

Term of patent 14 years

Int. Cl. D8—99

U.S. Cl. D41—1

FIG. 1

FIG. 2

FIG. 4

FIG. 3

FIG. 6

FIG. 5

FIG. 1 is a perspective view of a wheel chock embodying our new design;

FIG. 2 is a side elevational view thereof;

FIG. 3 is a rear elevational view thereof;

FIG. 4 is a bottom plan view thereof in reduced scale;

FIG. 5 is a perspective view of another embodiment of a wheel chock embodying my new design; and

FIG. 6 is a bottom plan view of the embodiment illustrated in FIG. 5.

We claim:

The ornamental design for a wheel chock, as shown and described.
